UNITED STATES PATENT OFFICE.

ABRAHAM RITTER, OF NEW YORK, N. Y.

COMBINED GARMENT-CLASP AND BELT-HOLDER.

SPECIFICATION forming part of Letters Patent No. 668,391, dated February 19, 1901.

Application filed December 18, 1900. Serial No. 39,702. (No model.)

To all whom it may concern:

Be it known that I, ABRAHAM RITTER, a citizen of the United States, residing in the borough of Manhattan, in the city and State 5 of New York, (whose post-office address is No. 2 East Ninety-seventh street, in said borough,) have invented certain new and useful Improvements in a Combined Garment-Clasp and Belt-Holder, of which the following is a 10 specification.

My invention relates to a clasp adapted to clip the waist of the trousers and drawers in proper relative position and also to retain a belt employed to surround and conceal the 15 upper edge of the trousers. These objects I effect by the improved construction herein-after described, and particularly pointed out in the claims.

In the accompanying drawings, Figure 1 is 20 a side view showing the garment-clasp and belt-retainer open. Fig. 2 is a side view showing the clasp and belt-holder closed and the belt and waistbands of the garments in section. Fig. 3 is a bottom view of the same.

Fig. 4 is a side view showing a modification.

A represents the front plate of the clasp, united at top with a stiff plate B, so as to form a hook to engage over the upper edges of the trousers T and drawers D and confine them 30 in proper relative position.

Pivoted to the lower end of the front plate A is an arm C, having inturned ends c and c', so that when turned up in the position shown in Figs. 2 and 4 the said arm C rests in 35 position parallel with the front plate A of the hook and at a distance therefrom and forms a loop for the reception of the waist-belt W. On the end c of the arm C, by which it is pivoted to the front plate A, is formed or mounted 40 a projecting lug F, which is thrown into the horizontal position (shown in Figs. 2 and 4) when the arm C is turned up.

H represents a spring-clip riveted by one end at h to the inner side of the plate A and 45 at its other end bent in a horizontal position, where it is formed with serrations or teeth h' to engage the surface of the trousers, so as to lock the clasp in position, while it tightly clips together the upper edges of the trousers and 50 drawers, as shown in Figs. 2 and 4. The spring-clip H is forced into this position by

pressure of the lug F when the arm C is turned up, and the said clip retires by its resilience from the hook-plate B when the arm C is turned down and throws the lug F into 55 the retracted position, (shown in Fig. 1,) thus releasing the hook and permitting its removal. The lug F is so disposed with reference to its pivot that in locking it passes beyond the radial line of pressure, so that the 60 pressure of the spring-clip H tends to hold the parts in the clasped position.

A transverse groove or notch b is made in the inner face of the hook-plate B directly opposite the edge h of the clip H to render its 65 grip on the garments more secure. The spring-clip H being attached wholly to the front member A of the clasp leaves the hook-plate B without any protuberance or obstruction to prevent inserting it over the edge of the garments while on the person.

The outer part C' of the arm C, including the inwardly-projecting upper end c', forms the face-plate of the combined garment-clasp and belt-holder and is suitably ornamented. 75

The spring-clip H may be riveted by its upper end to the plate A, as shown at h in Figs. 1 and 2, with its free end projecting downward, or it may be riveted at its lower end, as shown at h in Fig. 4, with its free end projecting upward.

Having thus described my invention, the following is what I claim as new therein and desire to secure by Letters Patent:

1. The combination of the front plate A having a downturned hook-plate B; the spring-clip H, fastened by one end h to the inner face of the front plate and having a horizontally-projecting serrated free end h'; the projecting lug F pivoted on the inner face of the 90 front plate A and operating to force the spring-clip H into locking position; the arm C rigidly connected by an inturned end c to the lug F for turning the same and a suitable face-plate C' mounted on the front of the arm 95 C, substantially as shown and described.

2. The combination of the front plate A; hook-plate B; the arm C having projecting ends c and c', the first pivoted to the lower end of the front plate A and the second resting against the face of said front plate near its upper end, so as to maintain the plate A 100

and the body of the arm C in parallel position with a space between, thus adapting them to serve as a belt-loop; the spring-clip H fastened by one end to the inner face of the plate

5 A and having a horizontally-projecting serrated free end; and the lug F rigidly mounted on the pivot end c of the arm C and forcing

the spring-clip H into locking position when the arm C is turned up into position to form a belt-loop, as described.

ABRAHAM RITTER.
